LINK CHAIN FOR AN EXPANSIBLE BRACELET OR THE LIKE

Samuel Meyerson, West Hempstead, N. Y.

Application December 13, 1952, Serial No. 22,698

Term of patent 7 years

(Cl. D45—4)

To all whom it may concern:

Be it known that I, Samuel Meyerson, a citizen of the United States, residing in West Hempstead, county of Nassau, State of New York, have invented a new, original, and ornamental Design for a Link Chain for an Expansible Bracelet or the like, of which the following is a specification, reference being had to the accompanying drawing, forming part thereof, in which,

Figure 1 is a top plan view of a link chain for an expansible bracelet or the like embodying my new design, a portion of the center being broken away for convenience of illustration;

Figure 2 is an edge view of the link chain as shown in Fig. 1, the conventional bottom links being shown in broken lines;

Figure 3 is a view similar to Fig. 1 but with the links in an expanded position;

Figure 4 is an enlarged perspective view of one of the top links;

Figure 5 is a side elevational view of links shown in Fig. 4;

Figure 6 is an end elevational view of links shown in Fig. 4.

The dominant feature of the invention resides in the elements shown in full lines.

I claim:

The ornamental design for a link chain for an expansible bracelet or the like, as shown and described.

SAMUEL MEYERSON.
